UNITED STATES PATENT OFFICE.

WALTER H. HUTH, OF CHICAGO, ILLINOIS.

TALKING-MACHINE REPEATER.

Application filed March 2, 1922. Serial No. 540,441.

To all whom it may concern:

Be it known that I, WALTER H. HUTH, a citizen of the United States, and a resident of Chicago, Cook County, Illinois, have invented a certain new and useful Improvement in Talking-Machine Repeaters, of which the following is a specification.

This invention relates to talking machine repeaters of that kind in which the device is operated by frictional contact with the record, and is released by the needle or stylus as soon as the playing of the record is finished, whereby the device is then free to turn around and lift the reproducer and return it to the starting point of the record.

Generally stated, the object of the invention is to provide a novel and improved talking machine repeater of the foregoing character, having certain novel features and details of construction whereby the device will operate more satisfactorily than heretofore, and will be practicable to manufacture, as will hereinafter more fully appear.

To these and other useful ends the invention consists in matters hereinafter set forth and claimed and shown in the accompanying drawings in which—

Figure 1 is a plan of a talking machine repeater embodying the principles of the invention, showing the same in place on the disc record of the phonograph or talking machine, and showing the reproducer of the machine in position for playing the record.

Figure 2 is a detail section on line 2—2 in Figure 1.

Figure 3 is a view of the end side of a portion of the said repeating device.

Figure 4 is an edge view of the part shown in Figure 3.

Figure 5 is a transverse section on line 5—5 in Figure 3.

Figure 6 is a detail view of a portion of the device.

As thus illustrated, the invention comprises a body formed from a single piece of sheet metal, said body comprising the portion 1 having upturned flanges 2 and 3 at each side thereof, and the narrow portion 4 having a rubber bushing 5 which fits over the center post 6 of the turntable 7 of the talking machine, whereby the repeating device is adapted to rest on top of the record 8 which is flat and of ordinary disc form. The portion 4 has the said flange 2 on a portion thereof, as shown. It will be seen that the flange 2 extends around and along

the inner edge of the portion 4, adjacent the bushing 5, which latter may be of rubber vulcanite or fiber of any other suitable material. At 9 the flange 2 is integrally united with the narrow portion 4, and with this construction a cam groove 10 is formed between the two flanges 2 and 3, which groove is wide at its mouth or front end, as between the points 11, and is narrow at the point 12 where it terminates at its rear end adjacent the operative position of the reproducer 13 of the talking machine. Thus a large and elongated opening is formed between the narrow portion 4 and the flange 2, thus reducing weight, and whereby the repeater has a skeleton like form. The flange 3 is integral with the horizontal flat portion 14 which is provided with a knob 15 having its lower end provided with a pointed foot 16 disposed in position to rest on the outer edge portion of the record, this foot being preferably a peg of rubber vulcanite or of fiber or some other material which will ride on the smooth outer surface of the record in the desired manner. The flat portion 14 extends along and terminates in the end portion 17 which has an inturned integral portion 18 disposed in a horizontal plane, and a sheet metal slide 19 is provided with guides 20 which engage the parallel edges of the portion 18, so as to slide endwise thereon. This slide carries on its upper surface a plate 21 of soft rubber or other similar material against the edge of which the stylus 22 of the reproducer rests and travels slowly along toward the center post 6 during the playing of the record. When the needle or stylus slips off at the corner 23, as it ultimately will, the device constituting the repeater is then whirled around with the record until the edge 24 thereof strikes the needle or stylus and the latter is then lifted and caused to travel between the flanges 2 and 3 until the point of the needle slips off at the edge 25, and when this occurs the needle or stylus is again where it started and in position to play the record again. The portion 18 has a notch 26 in one edge thereof and a small spring 27 is placed therein to bear against the inner surface of one of the guides 20, thereby to provide the friction necessary or desirable to hold the slide 19 in adjusted position, depending upon the width of the surface covered by the grooves of the record. The end 28 of one guide 20 engages in the corner or angle

29 of the portion 18 to limit the sliding movement of the slide 19 in one direction, and the inwardly bent portion 30 at the end of the other guide 20 will engage the 5 shoulder 31 formed in one edge of the portion 18 to limit the movement of said slide in the opposite direction. A felt pad 32, or other suitable material, secured to the bottom of the portion 17, rests upon the outer 10 smooth marginal portion of the record, and a similar pad 33 on the bottom of the portion adjacent the edge 24 rests on the record to support the device at this point, whereby sufficient frictional contact is provided be- 15 tween the record and the repeating device to carry the latter around when released by the stylus or needle of the reproducer. The soft rubber 21, or other suitable non-resonant material, does not interfere with the vi- 20 bration of the needle or stylus 22, and does not communicate said vibrations to the sheet metal repeating device, whereby the repeater is held in normal position by engagement with the needle or stylus but does not 25 interfere with the proper action of the lat- ter. Of course, the slide may have any suit- able means for engaging the needle or stylus, if desired. The width of the area covered by the grooves in the record varies, some- 30 what, on different records, but by means of the slide 19 the device is adjustable for differ- ent records, in a manner that will be readily understood, the entire means against which the needle or stylus bears being adjustable 35 toward and away from the center of the record to ensure a release of the needle or stylus at the proper time as soon as the playing of the record is finished. The wide mouth of the single cam groove is substan- 40 tially or approximately diametrically op- posite the means 21 for engaging the needle, and the wide mouth and the other end of the cam groove are also substantially and diametrically opposite. The sheet metal 45 from which the body of the device is made is preferably hardened steel, or some similar metal or material, and is of such character that a hard and highly polished surface is provided on the upper surface thereof over 50 which the point of the needle or stylus may travel without scratching. In other words, the sharp point of the needle or stylus will slide smoothly without scratching the de- 55 vice, and without injuring the point of the needle, when the device is whirled around by the rotation of the record, and a glassy surface, so to speak, is provided over which the point of the needle may slide practically 60 without friction in order not to catch and hold the repeater against turning around in the required manner. In other words, if the upper surface of the repeater were comparatively soft, or should the repeater be made of such material that the needle 65 would cut in or drag on said surface, the

needle being harder than the material, the device would not serve the desired purpose in a satisfactory manner, as a tendency toward scratching would obviously interfere. The entire weight of the reproducer, 70 of course, is supported by the point of the needle or stylus 22 on the hard and polished upper surface of the sheet metal reproducer, and the only point of connection between the repeater and the reproducer, at all times, 75 is at the point of engagement between the needle and the reproducer. This engagement alternates, of course, between the engagement of the needle along the edge of the rubber strip 21 and the sliding engage- 80 ment of this point over the smooth and highly polished, and practically glassy, upper surface of the reproducer. With the exception of a few parts, therefore, the entire reproducer is formed from sheet metal pressed by dies, or in any other suitable manner, into the desired shape. With this construction it is practicable to manufacture the repeater by simple shop methods at a comparatively minimum cost 85 of production.

It will be seen that the bottom of the groove 10 is flat and is sufficiently wide throughout its length to permit lateral move- 90 ment of the needle thereon at any point 95 along the length of the groove. In this way, therefore, the point of the needle does not follow a beaten path, so to speak, but can always follow a new path, thus avoiding the danger of cutting a groove in the repeater, and avoiding the danger of dulling the needle. In other words, the sharp point 100 of the needle always travels on a smooth and glassy surface which it does not scratch and which does not dull the point. More- 105 over, the turned up edges 2 and 3 of this groove also form the inner and outer edges of the repeater body.

It will be seen that the contact between the repeater and the record is concentrated at a 110 plurality of small spots, so that friction is reduced to a minimum, but the foot or peg 16 is so far from the center post *b* that even this slight friction is sufficient to whirl the repeater around in the desired manner. In- 115asmuch as the repeater is practically all at one side of a line extending from the mouth of the shallow groove 10 to the discharge end thereof, or a line thus intersecting the axis of the repeater, it follows that the repeater will be given a half turn and will acquire some momentum before the mouth of the groove strikes the needle or stylus 22, thus ensuring enough speed to carry the repeater around in the desired manner. Fur- 120 thermore, the slight friction existing be- 125tween the repeater and the record, when thus applied at the outer edge of the repeater, is sufficient to carry the repeater around under the needle because the latter slides so 130

easily on the glassy flat bottom of the groove 10 upon which the needle is always free to move laterally. Although formed of sheet metal of uniform thickness, pressed 5 into the desired shape, it will be seen that the repeater is rigid and stiff, inasmuch as the flanges 2 and 3 serve as stiffening means to prevent flexibility, and to thus ensure that the repeater will be maintained in a perfectly 10 flat condition. The metal of the repeater is not adapted to engage the record, and hence non-metallic means are provided for this purpose, as described.

As the hard and glassy surface of the shallow 15 groove 10 is horizontal, and is considerably wider than the needle throughout its length, it follows that the point of the needle is always free to move sidewise thereon, so that identically the same path is not followed 20 each time by the needle in returning to the starting point. Moreover, inasmuch as this shallow groove begins and terminates practically on a line intersecting the axis of the repeater, it follows that the repeater 25 not only acquires considerable momentum before it strikes the needle, but also the extent of travel of the needle on the glassy surface of the repeater is minimized, thus further ensuring against stoppage of the 30 machine by contact of the needle with the repeater. As previously stated, to obtain the hard and glassy surface hardened steel is employed, which may be produced in various well known ways, such as by case hardening, but it is obvious that, for the 35 broader purposes of the invention, the hard and glassy surface can be produced in any suitable or desired manner, by the use of any suitable or desired materials. Being glassy 40 in character, as stated, the surface is not only smooth and highly polished, but is also so hard, of course, that the needles commonly employed cannot scratch the surface, and because of this and the smoothness of the 45 surface the needle will not be dulled or injured by its sliding contact with said surface.

The action of the steel needle on the record results, of course, in gradually wearing 50 away the point of the needle, so that in some cases it becomes possessed of a chisel edge, or other ragged edge, or sharp corners, and this is true of some other needles which are commonly used for repeat purposes. However, 55 as the point of the needle slides on a hardened steel, it takes very little power to rotate the repeater, or practically the minimum of power, and it is found that the contact of the needle at its point with a hard 60 and glassy surface reduces the amount of power necessary to rotate the repeater.

In the use of a repeater it is desirable, of course, to minimize the load on the motor of the machine as much as possible, not only 65 to minimize the power necessary to rotate

the repeater under the needle or stylus, when the point of the latter drags on the repeater, as it does in this case, but also to minimize the power necessary to rotate the record under the repeater while the latter is stationary. Therefore, as shown and described, the contact between the repeater and the record is, by the means 5, 16, 33 and 32, reduced practically to a minimum, or just enough to overcome the friction between the 70 needle or stylus and the upper surface of the repeater. When the repeater is stationary, the record rotates smoothly under the repeater, with a minimum of additional load on the motor of the machine, and when the 80 repeater rotates with the record the hard and glassy surface of the repeater functions to advantage in several ways, to-wit:—First, the point of the needle or stylus, even though made of steel, passes almost without friction over the hard and glassy surface, just as the point of an ordinary sewing needle or other sharp point may be rubbed over a polished sheet of glass, thereby to 85 permit rotation of the repeater, notwithstanding the slight frictional contact that the repeater has with the record; second, the needle, although made of steel, does not scratch the repeater, and is not compelled to 90 follow the same path each time, but may find a different path each time it passes over the repeater, for everywhere the point of the needle has freedom of lateral movement while traveling across the repeater; third, the repeater, although hard and glassy and 95 even though harder than the needle, does not dull the needle, for while the hardness of the repeater prevents it from being scratched, the polished or glassy surface of the repeater, on the other hand prevents dulling 100 of the needle; and, while the hard and glassy surface could be obtained by using glass itself, it is obvious that something less breakable is desirable, and hence it is preferable to combine the hard and glassy surface 105 with the flexibility and strength of sheet metal, not only to provide an article which is strong and not breakable, but which is also susceptible of production by simple methods of manufacture to provide an article 110 which is rigid and substantial, not liable to injure the record or the needle, and yet comparatively inexpensive to manufacture. The pointed lower end of the peg 15 and 16 115 engages the smooth outer surface of the record with little or no friction, practically, and co-operates with the lower end of the bushing 5 to non-yieldingly support the repeater very close to but nevertheless just out of contact with the record. The pieces 120 of felt or other material 32 and 33 engage the repeater with a minimum of friction, and with very little pressure, and merely prevent the two metal ends of the repeater 125 from sagging or tilting down against the 130

record, so that the repeater although made from sheet metal has no metallic contact with the record. Being made of metal, the repeater has some weight and it acquires considerable momentum before its edge 24 strikes the needle or stylus, and here again the necessity for any extensive frictional surface between the record and the repeater is obviated, as the headway gained by the repeater when released by the needle is very nearly, if not quite, sufficient to carry its hard and glassy surface around under the point of the needle.

In Figure 1, it will be seen that line 2-2 divides the repeater into end portions of unequal weight, as the wide mouth of the groove 10 and the adjacent portions are heavier than the other end of this groove and adjacent portions. In other words, there is much more metal below the line 2-2, than there is above this line, in Figure 1, so that the repeater is heavier at 33 than it is at 32, and the repeater tends to tilt downward at 33 when supported by the bushing 5 and the peg 16 on the upper surface of the disc record. As shown clearly in Figure 2, the portion 14 is a greater distance above the record than is the bottom 10 of the groove, and it will be seen that the portion 17 is in the same horizontal plane as the portion 14, so that the under surface of the portion 17 is a greater distance above the record than is the lower surface at the other end where the pad 33 is attached. As shown clearly in Figure 4, the thickness of the soft pad 32 is much less than the vertical depth and thickness of the space between the portion 17 and the top surface of the record. Therefore, when the repeater is not engaged by the needle 22, the tendency is for the pad 33 to rest on the groove of the record, while the pad 32 is somewhat higher and out of engagement with the smooth outer rim portion of the record. However, when the needle 22 bears against the soft edge of the strip 21, there is a tendency then to tilt the portion 17 of the repeater downward, so that the pad 33 is slightly lifted, it being evident that the post 6 cannot have such a tight fit in the bushing 5 as would preclude the slight tilting of the repeater about the line 2-2 as an axis, in the manner stated. When the needle 22 releases the repeater, the greater weight of the metal below the line 2-2 causes the wide mouth portion of the needle groove to have a tendency to tilt downward until the pad 33 bears with sufficient friction against the grooves of the record to whirl the repeater around until the edge 24 strikes the needle. Very little friction is required between the pad 33 and the record to do this, inasmuch as the friction between the hard peg 16 and the smooth surface of the record, while as little as possible,

is barely sufficient to rotate the repeater when the latter is free, and being of some weight, the repeater would strike the needle 22 with considerable momentum, but the pad 33 will bear downward a little harder 70 as soon as the needle rises over the edge 24 and rests with the weight of the reproducer 13 on the repeater. At such time, the weight of the reproducer is carried by the repeater, and the pad 33 ensures sufficient friction to 75 propel or rotate the repeater under its load weight. When the needle is close to the small end of the groove, and when it engages the strip 21, the tendency then, as stated, is to slightly raise the pad 33, and the pad 32 will only engage the record in the event that the depression of the portion 17 is sufficient, and the pad 32 will act as a cushion to prevent the metallic portion 17 from striking the record. While the record is 80 being played, the tendency is, therefore, for the pad 33 to rise a little, and for the pad 32 to bear only very slightly, if at all, against the smooth outer surface of the record, so that at such time the weight of the 85 repeater is carried practically entirely by the bushing 5 and the peg 16, and inasmuch as the elements 5 and 16 are hard and engage only the polished smooth surfaces of the record, it follows that there is only a minimum of friction between the repeater and the record while the record is being played. Therefore, it is not only true that contact 90 of the repeater with the record is reduced in area, and practically to a minimum, but it is also true that the coefficient of friction of the materials from which the bushings 5 and the peg 16 are made is less than the coefficient of friction of felt or cloth or other soft material from which the pads 32 and 95 100 105 110 115 120 125 130 135

33 are made, so that the friction between the repeater and the record is in fact practically reduced to a minimum. The friction between the point of the needle and the upper surface of the repeater, however, is even less, as explained, and the consequence is that the very slight friction between the record and the repeater, especially when augmented by the added friction of the pad 33 against the grooved surface of the record, is just sufficient to rotate the repeater under the weight of the needle and the reproducer, without adding but very little to the load imposed on the motor of the machine. For example, where soft material is used for a repeater, of such character that the sharp point of a steel needle will even very slightly scratch the top surface of the repeater, much more friction is then required between the repeater and the record, and the result is not only an added load on the motor, but also the further objection that the repeater is whirled around so suddenly that it will strike the needle a hard blow, which is objectionable for obvious reasons. 130

With the construction shown and described, however, the repeater when released by the needle starts to rotate rather gradually, and being of some weight acquires some momentum, but the friction between the record and the repeater is so slight that the repeater does not strike the needle with too much force, but rather gently and with just enough momentum and propelling power to 5 elevate the needle and to allow the point of the latter to then slide practically without friction over the glassy surface of the repeater until the needle drops off and again engages the soft edge of the strip 21 in the 10 manner described.

What I claim as my invention is—

1. In a repeater for talking machines, in combination, a body having retaining means to engage the stylus or needle of the machine 20 during the playing of the record, to retain the repeater against rotation, and having guiding means to return the needle or stylus to starting point on the record, supporting means on said body to engage the center post 25 of the turntable of the machine, supporting means on said body to engage the smooth outer surface of the record, with the greater portion of the weight of said repeater at one side of a radial line intersecting the points 30 of contact of said two supporting means on the record, so that the mouth of said guiding means at one side of said line tends to tilt downward about an axis approximating said radial line, while said retaining means at the 35 other side of said line tends to tilt upward, and engaging means on said body to bear against the record at opposite sides of said radial line, the engagement of the stylus or needle with said retaining means tending to 40 tilt this lighter end of the repeater downward, whereby during playing of the record the weight of the repeater is mostly if not entirely on said supporting means and pressure of said engaging means is reduced on 45 the record, the bottom of said guiding means being hard and glassy and of sufficient width to provide a different path each time for the point of the needle, thereby to minimize the friction between the needle and the repeater, and thereby to enable said supporting 50 and engaging means to function with as little friction as possible.

2. In a talking machine repeater, the combination of a metal support having means thereon for engaging the needle or stylus of the machine, to hold the repeater in normal position while the record is being played, said engaging means having a soft edge in position for preventing contact of the needle 55 with the metal support, and means to automatically return the needle to the starting point when it is released from the yielding edge of said means.

3. In a talking machine repeater, a sheet 60 metal body formed to engage and return the

point of the needle of the machine over a different path each time to starting point on the record, to reduce to a minimum the friction between the repeater and the point of the needle, a center bushing of non-metallic substance to engage the center post of the machine, to support the repeater on the record, non-metallic means to support the repeater by restricted or small spot engagement on the smooth outer marginal portion of the record, co-operating with said bushing to prevent the metal body from directly engaging either said post or the record, with so little friction that the record rotates freely under the repeater, but ensuring just enough friction between the record and said body to rotate the repeater when released by the needle, and other non-metallic means to ensure sufficient friction to rotate the repeater under the weight of said needle. 70

4. A structure as specified in claim 3, said last mentioned non-metallic means being disposed at a single point on the bottom of said body to engage the grooves of the record. 85

5. A structure as specified in claim 3, said non-metallic substance and means being disposed at the three corners of a triangle, forming three small and widely separated points of contact with the record. 90

6. In a talking machine repeater, the combination of a body adapted to return the needle of the machine with a minimum of friction to starting point on the record, by each time permitting the point of the needle to find a different path of travel thereon, and means 95 to support the repeater by restricted engagement at a small point traveling on the smooth outer marginal portion of the record, to provide practically only a minimum engagement with said surface, adapted to reduce friction to the minimum necessary to prevent slowing of the record under the repeater, but just sufficient to rotate the repeater when released by the needle. 100

7. In a talking machine repeater, a rigid 110 sheet metal body formed from a flat horizontal section of sheet metal of uniform thickness and having the edges thereof bent upward to form stiffening means and to form a single wide mouthed and gradually 115 narrowing cam groove to return the needle of the machine to starting point on the record, so that the edges of the groove form the inner and outer edges of said body, with the bottom of said groove formed with a 120 flat surface adapted to engage the point of the needle, so that the needle may each time follow a different path thereon, and means adjacent the terminal of said groove to engage the needle to hold the repeater against 125 rotation until after the record is played.

8. A structure as specified in claim 7, one of said edges being bent over horizontally and extended outward in a plane above the bottom of said groove and provided with 120

supporting means forming a small spot on the bottom of the repeater to engage the smooth outer marginal surface of the record.

9. A structure as specified in claim 7, in combination with means forming a small spot on the bottom of the repeater at the mouth and also at the terminal of said groove to support said body on the record with the minimum of friction necessary to rotate the repeater and permit the point of the needle to slide freely on the bottom of said groove and to prevent slowing of the record under the repeater.

10. In a repeater for talking machines, a one-piece rigid body formed from hard sheet metal of uniform thickness extending in a horizontal plane having the inner and outer edges thereof turned up to form flanges having a shallow groove between them with a hard glassy flat bottom upon which the point of the needle may slide freely and find a different path of travel each time while being returned automatically to the starting point by the rotation 25 of the repeater on the record, having means to engage the needle to hold the repeater against rotation during the playing of the record.

11. A structure as specified in claim 10, all of said repeater being practically at one side of a line intersecting the axis thereof, thereby to minimize the extent of travel of the point of the needle on said bottom, and to ensure sufficient momentum of the repeater before striking the needle.

12. A structure as specified in claim 10, having a narrow supporting portion which connects the mouth of said groove with the discharge end thereof and which has means to engage the center post of the machine, 40 with an elongated opening between said post engaging portion and one edge of said groove so that said groove is spaced by said opening from the axis of the repeater.

13. A structure as specified in claim 10, said groove formed by said flanges being wide enough throughout the length thereof to permit some freedom of lateral movement of the point of the needle on said bottom.

14. A repeater for talking machines, comprising means for engaging the needle or stylus of the machine to hold the repeater against rotation during the playing of a record, and sheet material to provide a groove for guiding the needle back to starting point, said material being hard steel to provide a glassy surface for the point of the needle to slide on, and having bent portions to form said groove and also render the repeater stiff and rigid.

15. A repeater for talking machines, comprising a body of sheet material formed to provide a return groove with a bottom for the point of the needle of the machine to

slide on, having an integral and inwardly extending flat arm adjacent the rear end of said groove, and a flat slide overlying and superposed on said arm to slide endwise thereon to in effect extend the length of said arm and formed with an edge to engage said needle.

16. A structure as specified in claim 15, said flat movable slide having a flat strip of rubber secured thereon to form a yielding edge to engage the needle.

17. In a talking machine repeater, a flat body of sheet material formed with a channel member having its inner and outer edges turned up to form flanges, providing a shallow trough for guiding the needle of the machine back to starting point, with a flat horizontal bottom for the point of the needle to slide upon, means to engage the needle to hold the repeater against rotation during the playing of the record, integral means having one of said flanges thereon and extending from the mouth of said member to the rear end thereof to engage the center post of the machine, with an opening between said member and said integral means, and means to support said body on the record.

18. A structure as specified in claim 17, said body and integral means comprising a single piece of hardened sheet metal to provide said bottom with a hard and glassy surface for the point of the needle.

19. A structure as specified in claim 17, said trough forming a gradually tapering shallow groove which is wide enough everywhere to permit some freedom of lateral movement of the point of the needle on said bottom.

20. In a repeater for talking machines, in combination, a body having retaining means to engage the stylus or needle of the machine during the playing of the record, to retain the repeater against rotation, and having guiding means to return the needle or stylus to starting point on the record, supporting means on said body to engage the center post of the turntable of the machine, supporting means on said body to engage the smooth outer surface of the record, with the greater portion of the weight of said repeater at one side of a radial line intersecting the points of contact of said two supporting means on the record, so that the mouth of said guiding means at one side of said line tends to tilt downward about an axis approximating said radial line, while said retaining means at the other side of said line tends to tilt upward, and engaging means on said body to bear against the record at opposite sides of said radial line, the engagement of the stylus or needle with said retaining means tending to tilt this lighter end of the repeater downward, whereby during playing

of the record the weight of the repeater is mostly if not entirely on said supporting means and pressure of said engaging means is reduced on the record.

5 21. A structure as specified in claim 20, said supporting means being of relatively hard material, and said engaging means being of relatively soft material, so that said supporting means are non-yielding

10 while said engaging means have a yielding

contact with the record, and the greater pressure of the heavier end of said repeater on the record when released by said retaining means increasing the friction to rotate the repeater under the needle until the point 15 of the latter crosses said line, and whereby after the needle has crossed said line the friction between the repeater and the record is reduced to a minimum.

WALTER H. HUTH.
